APPARATUS AND METHOD FOR MAKING
CURLED YARN

Edgar Greenwood, Lowell, Mass., assignor to Massachusetts Mohair Plush Company, Lowell, Mass., a corporation of Massachusetts

Application December 28, 1946, Serial No. 718,964

12 Claims. (Cl. 57-3)

1

This invention relates to the making of curled yarn such as is used in weaving certain types of fabric which include in their structure a yarn having a permanent curl or wavy effect.

One known method used for producing curled yarn is to wind or wrap the yarn to be curled about a core strand thereby to produce a composite strand composed of the core strand and the winding thereabout, and then to steam or otherwise treat the composite strand to set the curl in the yarn which is wound about the core strand, after which the yarn is unwound from the core and may be rewound on a suitable yarn carrier for use in the weaving operation. The treatment to which the composite strand is subjected is such that when the yarn is thus unwound from the core strand, it will have the desired permanent curl or wavy effect.

The means heretofore employed for winding the yarn to be curled about the core strand is so constructed that there are definite limits to the length of the yarn that can be so wound at any one operation. In large textile mills there is often a demand for curled yarn ends several thousand yards in length, but to fill such an order, it has heretofore been necessary to curl the yarn in relatively short lengths because of the limitations imposed by the mechanism heretofore used in wrapping the yarn to be curled about the core strand.

One of the objects of my invention is to provide an apparatus for use in making curled yarn by which a greatly increased length of yarn to be curled can be wound about the core strand at a single operation, thus making it possible to produce unbroken, continuous lengths of curled yarn several times as long as could be made by means of the mechanism heretofore used.

A further object of the invention is to provide an apparatus for use in making curled yarn which produces a composite strand of such a character that after it has been treated to set the curl in the individual yarn ends comprising the plural ply strand, the core strand can be readily removed from the composite strand without unwinding the plural ply strand therefrom, thereby leaving the plural ply strand in a tightly coiled condition, said plural ply strand being of such a character that a pulling force applied thereto in the direction of its length will stretch said strand into one in which the individual curled yarn ends lie parallel to each other and in a non-twisted relation so that said individual curled yarn ends are ready for immediately being wound on individual bobbins or other yarn carriers.

2

A further object of the invention is to provide an improved method of making a composite strand of the above type.

In the drawings wherein I have illustrated a selected embodiment of my invention:

Fig. 1 is a plan view of a device embodying my invention for producing the composite strand above referred to.

Fig. 2 is a side view of Fig. 1.

Fig. 3 is a longitudinal sectional view on substantially the line 3-3, Fig. 1.

Fig. 4 is an enlarged sectional view of the core strand carrier.

Fig. 5 is a section on the line 5-5, Fig. 3.

Fig. 6 is an enlarged view illustrating the character of the composite strand produced by the apparatus shown, and also illustrating the manner in which the individual curled yarn ends may be withdrawn directly from said strand after the core strand has been removed.

Fig. 7 is a fragmentary view showing a different embodiment of the invention.

Fig. 8 is a view illustrating one way in which the core strand can be removed from the composite strand.

Referring first to Fig. 6 which shows the product produced by the machine, 1 indicates the core strand, and 2 indicates the plural ply strand of yarn to be curled which is wound or wrapped tightly about the core strand to produce the composite strand 3.

The apparatus herein disclosed comprises a source of supply for the core strand 1 from which it is delivered, a stationary source of supply for the yarn to be curled, feeding means to feed the core strand forward, and means acting on the portion of the yarn to be curled between its stationary source and the feeding means to carry said yarn bodily around the core strand supply thereby wrapping the yarn to be curled about the core strand as it is delivered from said supply.

Where the yarn to be curled and wrapped around the core stand is in the form of a plural ply strand in which the yarn ends lie parallel but with a non-twisted relation, the operation of carrying such plural ply strand around the source of supply for the core strand is so carried out that the threads in the plural ply strand will remain in their non-twisted relation as they are wound about the core strand, and after the composite strand has been treated to set the curl in the yarn ends of the plural ply strand, and the core strand has been removed, the coiled plural ply strand can be converted into a strand composed of parallel curled yarn ends having a non-

twisted relation.

twisted relation by simply applying to said coiled plural ply strand a pulling force in the direction of its length.

The core strand 1 is herein shown as being supplied from a bobbin 3 which is mounted on a rotary bobbin carrier 4, the latter having a bearing portion 5 which is mounted for rotation in a suitable bearing 6 that is carried by a base or supporting member 7. The bobbin carrier 4 is provided with a suitable tension device 8 through which the core strand passes as it leaves the bobbin or spool 3 thereby to produce in the core strand a desirable tension. From the tension device 8 the core strand 1 extends through a guide 9 with which the carrier 4 is provided and thence through an axial passage 10 with which said carrier is also provided. The bobbin carrier 4 is also provided with a conical projecting nose portion 11 at the delivery end of the passage 10. The bearing portion 5 of the carrier 4 is made with a central axial passage 12 through which the composite strand is delivered.

The source of supply for the yarn to be curled is shown as in the form of a creel 13 carrying a plurality of spools 14 from each of which a yarn end is withdrawn. These various yarn ends are lead from the spools through a trumpet or eye 15 where they are condensed into a plural ply strand 2 in which the individual yarn ends lie parallel to each other but in a non-twisted relation. Such plural ply strand extends past the core strand supply bobbin 3 outside of the latter and through a guide opening 16 formed in the carrier 4, said plural ply strand extending then to the nose portion 11 of the carrier where it is wrapped around the core strand 1 to produce the composite strand 38.

For this purpose the bobbin carrier 4 is rotated about its axis, and during such rotation, the portion 17 of the plural ply strand 2 is carried bodily around the core strand bobbin 3, this operation resulting in the winding of the plural ply strand 2 about the core strand 1 as shown in Fig. 6.

For thus rotating the carrier 4, the portion 18 thereof is provided with gear teeth 19 which mesh with and are driven by a gear 20 on a drive shaft 21 that is mounted in suitable bearings 22 carried by the base or supporting frame 7. The shaft 21 may be driven from any suitable source of power and is herein shown as having a driving pulley 23 thereon which may be connected by a driving belt with any prime mover.

Means are provided for feeding the core strand 1 forward as the plural ply strand 2 is wrapped thereabout. Such feeding means are illustrated as feed rolls 24, 25, 26 which are journaled in a suitable support 27 carried by the base 7, said feed rolls being conveniently driven from the drive shaft 21. For this purpose the drive shaft is shown as having a worm 28 fast thereon which meshes with and drives a worm gear 29 mounted on a stub shaft 30 carried by the stand 27. Said gear 29 has fast therewith a gear 31 which meshes with and drives a gear 32 that is rigid with the lower feed roll 24 and situated at one end thereof. The opposite end of said feed roll 24 has a gear meshing with an intermediate gear 33 which in turn meshes with and drives a gear 34 fast on the shaft of the upper roll 26.

The composite strand 35 is shown as passing under the lower feed roll 24 and then between the latter and the intermediate feed roll 25 and partly around the latter and then between the feed rolls 25 and 26.

As stated above, the operation of winding the plural ply strand 2 of the yarn ends to be curled about the core strand 1 is accomplished by carrying the portion 17 of said plural ply strand bodily around the core strand bobbin 3, the plural ply strand being wrapped about the core strand as the latter leaves the tubular nose portion 11, it being understood that such bodily movement of the portion 17 of the plural ply strand about the core strand bobbin 3 is accomplished by the rotation of the bobbin carrier 4 and the fact that the plural ply strand is lead through the guide opening 16 of said carrier 4. The carrier 4 is formed with a head portion 36 in which the guide eye 9 for the core strand 1 is formed. The peripheral edge of this head 36 is smooth, and in its forward travel, the plural ply strand 2 contacts with the periphery of said head as shown in Figs. 3 and 4.

Associated with the guide eye 15 are a pair of rollers 37 rotatably mounted in a support 38 and between which the plural ply strand 2 is lead after it leaves the guide eye 15, said rollers 37 serving to apply a suitable tension to the strand 2. The individual yarn ends or piles making up the plural ply strand are substantially parallel to each other and in a non-twisted relation, and this parallel non-twisted relation of the individual yarn ends is maintained in the portion 17 of said plural ply strand while it is being rotated about the core strand supply and still exists in said strand as it is wrapped about the core strand, and hence in each turn of the plural ply strand about the core strand the individual yarn ends have such parallel non-twisted relation.

The core strand supply bobbin 3 is so mounted that its axis is out of line with the nip of the rolls 37, the construction illustrated being such that the axial line of the core strand bobbin 3 is below the nip or said rolls. As a result of this offset relation between the bobbin 3 and the rolls 37, the plural ply strand 2 will be subjected to an increased tension or pulling force when it is passing around the under side of the bobbin 3 as illustrated in Figs. 3 and 4, and such tension or pulling force will be relieved when the bobbin and its carrier have made a half revolution so that the plural ply strand 2 is on the upper side of the bobbin. The plural ply strand is thus periodically subjected to an appreciable tension or pulling force, and such tension or pulling force is released between each period, and as shown in the drawings the increased pulling force or tension is applied during one part of each revolution of the carrier 4 and such pulling force or tension is relieved during another part of each such revolution. Each time that the increased tension or pulling force is applied, the plural ply strand will be fed forward from its source of supply, and when the pulling force or tension is relieved, as it is when the strand is passing over the top of the bobbin, said plural ply strand will be slightly slack.

During the period in which the plural ply strand is slack, the individual yarn ends of the plural ply strand where they are being delivered to the nose portion 11 of the carrier, will become readjusted relative to each other as necessary so that the strands are delivered to the nose 11 and wrapped thereabout in a non-twisted relation.

While the actual wrapping or winding of the plural ply strand 2 about the core strand occurs at the end of the nose 11 where the core strand

is delivered from said nose, yet during the operation of the apparatus and as a result of the offset relation between the bobbin 3 and the nip of the rolls 31, there will be one or two turns of the plural ply strand 2 about the end of the nose 11 as shown at 38.

The spacing of the adjacent turns of the plural ply strand 2 as it is wound about the core strand depends on the relation between the forward feeding movement of the composite strand 35 and the speed of rotation of the bobbin carrier 4. The device shown in Figs. 1 to 3 is intended to operate so as to produce a composite strand 35 in which the turns of the plural ply strand will be close together as shown at the left in Fig. 6, and said plural ply strand will be tightly wrapped about the core strand. This way of wrapping the plural ply strand about the core strand will produce individual curled yarn ends 52 having a relatively tight curl as illustrated at the right in Fig. 6.

In Fig. 7 there is shown a construction which provides for adjusting the speed of feeding movement of the composite strand. In this embodiment of the invention the shaft 30a of the worm gear 29a is mounted in a carriage or support 10 which is adjustably mounted on the bed 1a so that it can be moved toward and from the stand 21a in which are mounted feed rolls corresponding with the feed rolls 24, 25 and 26 of Fig. 3.

In this embodiment of the invention the gear 31a which meshes with the gear 32a is a change gear and can be removed from the shaft 30a and replaced by another gear of a different size. The adjustability of the stand or carrier 10 provides for maintaining the proper meshing relation between the gears 31a and 32a regardless of the size of the gear 31a.

If a larger gear 31a is used than that shown in Fig. 2, the speed of the feed rolls 24, 25, 26 will be increased and as a result the turns of the plural ply strand about the core strand will be separated somewhat, the amount of such separation depending upon the size of the gear 31a.

If the plural ply strand 2 is so wound about the core strand that the turns of the plural ply strand are spaced from each other, the result will be that when the composite strand has been treated to set the curl and the plural ply strand has been reduced to its individual curled yarn ends, said yarn ends will have a wavy instead of a tightly curled condition. For some purposes, it may be desirable to produce a curled yarn having a wavy effect rather than a tightly curled effect and the provision of the change gear 31a makes it possible to produce a curled yarn with a more or less tightly curled effect.

The composite strand 35 may be wound on a suitable beam 39 by any suitable winding mechanism, and as herein shown, said beam is carried by a shaft 40 and it is driven through a friction drive 70 from a worm gear 41 that is loosely mounted on said shaft 40 and meshes with and in turn is driven by a worm 42 carried by the drive shaft 21. Associated with the beam 39 is a traverse mechanism 43 by which the composite strand 35 is properly laid on the beam 39. Said traverse mechanism may be of any usual type and that herein shown comprises a guide eye 44 through which the composite strand 35 passes and which is carried by a block 45 that is equipped with a shoe adapted to travel in the reversing cam groove 46 formed in a vertical shaft 47 so that the rotation of the shaft 47 will move the block

45 up and down or back and forth parallel to the axis of the beam 39.

The shaft 47 is driven from the shaft 40 carrying the beam 39, and for this purpose said shaft 40 has associated therewith a sprocket wheel 48 connected by a sprocket chain 49 to a sprocket wheel 50 fast on the shaft 47.

The core strand which I prefer to use is a plural ply twisted strand, that is, a strand made by twisting together two or more individual threads 51 and seen in Fig. 6. The direction of rotation of the bobbin carrier 4 is such as to take out the twist from the core strand with the result that when said strand is delivered from the nose portion 11 at the point where the plural ply strand 2 is wound thereabout, said core strand is in the form of a plurality of parallel ends 51 and has very little, if any, twist therein. The pulling strain which the feed rolls 24, 25, 26 impart to the composite strand in feeding said strand forward is taken by the core strand, and the advantage of a core strand which is without any appreciable twist and in which the plies lie practically straight and parallel is that a core strand of this type will have much less tendency to stretch than a core strand made up of a plurality of plies tightly twisted together.

The use of a substantially non-stretchable core strand between the points where the plural ply strand 2 is wound thereabout and the feed rolls avoids the possibility that the spacing of the turns of the plural ply strand 2 about the core strand will be changed by a stretching of the core strand during the forward feeding operation.

After said composite strand has been steamed or otherwise treated to set the curl in the individual plies of the plural ply strand 2, then the core strand 1 is removed thereby leaving the coiled plural ply strand in which the individual yarn ends have a parallel non-twisted relation, said coiled plural ply strand having such characteristics that the application of a pulling force to said plural ply strand in the direction of its length will convert the same from a coiled condition into one in which the individual curled yarn ends 52 have a substantially parallel non-twisted relation as shown in Fig. 6. While the application of the pulling force will tend to straighten the plural ply strand 2, yet when the pulling strain is released, the individual yarn ends will automatically assume their curled condition as shown at the extreme right in Fig. 6.

The core strand 1 may be removed from the composite strand in various ways without departing from the invention. One method of securing this result would be to cut the core strand into relatively short lengths on the order of two or three inches. This could be done by separating two adjacent turns of the plural ply strand sufficiently to insert the point of a pair of scissors or some other cutting tool into a position to cut the strand 1. If the strand 1 is cut into separate short lengths, then when the plural ply strand is pulled out from its coiled condition shown in Fig. 6, the short lengths of the core strand will simply fall away.

Another way of disposing of the core strand would be to make it of some synthetic material which could be dissolved by immersing the composite strand in a suitable solvent for the material of the core strand that would not have any chemical effect on the plies of the plural ply strand 2.

Still another way of removing the core strand 75 would be to unwind it from the composite strand

as shown in Fig. 8. This could be done by a suitable mechanism which would take the core strand and carry it around the composite strand as shown diagrammatically in Fig. 8, such operation withdrawing the core strand from between the successive turns of the coiled plural ply strand.

When the core strand has been thus removed, then the individual curled yarn ends 52 can be withdrawn directly from the curled plural ply strand by applying a pulling force to the yarn ends in the direction of the length of such coiled plural ply strand as shown in Fig. 6.

The plural ply strand is so formed that the individual yarn ends 52 composing the strand lie substantially parallel and in a non-twisted relation, both while the strand is in its coiled condition, and when the coiled strand has been straightened more or less by the application of a pulling force thereto. The individual curled yarn ends 52 can thus be taken directly from the coiled plural ply strand and wound on individual yarn carriers or bobbins ready for use in a weaving operation.

The arrangement herein shown by which the yarn ends comprising the plural ply strand 2 are taken from a creel or other stationary source of supply, and the manner in which said plural ply strand is wound about the core strand has this important advantage; that the length of the yarn ends 51 to be wrapped about the core strand in any one operation can be greatly increased over what is possible with methods now in use, such length being limited only by the capacity of the bobbin 3 carrying the core strand. The core strand may be relatively small so that a bobbin such as shown in the drawings will readily accommodate a core strand of several thousand yards in length.

The beam 39 on which the composite strand is wound may be of any desired size and may readily be of a size to receive a composite strand as long as the length of the core strand which is carried by the bobbin 3. This is an important feature from a commercial standpoint, because it provides for making long lengths of curled yarn at a single operation and avoids the necessity of making the curled yarn in relatively short lengths as has heretofore been done.

I claim:

1. A device of the class described comprising a rotary carrier, a bobbin carrying a core strand mounted on said carrier and arranged co-axially therewith, means to rotate the carrier and the bobbin carried thereby about the axis thereof, means to withdraw the core strand from the bobbin as the carrier rotates and feed it forward in the axial line of both the bobbin and the carrier, a stationary source of supply for the yarn to be curled situated in the rear of the carrier and from which is delivered a plural ply strand of such yarn made up of separate yarn ends having a parallel and non-twisted relation, means acting on a portion of such plural ply strand remote from its source of supply both to carry such portion repeatedly completely around both said bobbin and the core strand delivered therefrom thereby to wrap the plural ply strand around the core strand and to apply periodically to such portion of the plural ply strand an appreciable tension sufficient to feed it forward from its supply source and then to relieve such tension, whereby the individual yarn ends of the plural ply strand are in a non-twisted relation when so wrapped about the core strand.

2. A device of the class described comprising a rotary bobbin carrier, a bobbin carrying a core strand mounted thereon, said carrier having an axial passage through which the core strand is delivered, means to withdraw the core strand from the bobbin through said axial passage, means independent and spaced from the bobbin carrier for supplying a plural ply strand of the yarn to be curled to the carrier, the latter having a guide opening spaced radially from said passage near the delivery end thereof, said plural ply strand extending around the bobbin and through said guide opening to the end of said axial passage, and means to rotate the bobbin carrier thereby to carry the plural ply strand around the bobbin and to wrap said plural ply strand about the core strand as it is delivered from said passage.

3. A device of the class described comprising a rotary bobbin carrier, a bobbin carrying a core strand mounted thereon, said carrier having a nose portion and an axial passage which extends through and terminates at said nose portion, and also having a guide opening spaced radially from said axial passage, feeding means to withdraw the core strand from the bobbin and through said axial passage, a stationary source of supply for the yarn to be curled from which a plural ply strand of such yarn is delivered, said plural ply strand extending around the bobbin and through said guide opening to the end of the nose, and means to rotate the carrier thereby to carry the plural ply strand around the bobbin and to wrap it tightly about the core strand as the latter emerges from the axial passage.

4. The method of making curled yarn which comprises withdrawing a core strand from a source of supply, withdrawing from a stationary source of supply a plural ply strand of the yarn to be curled in which the individual yarn ends lie straight and parallel and in a non-twisted relation, and delivering said plural ply strand while in such non-twisted relation to the core strand after the latter has been withdrawn from its source of supply, carrying the portion of the plural ply strand between its stationary source of supply and the point where it is delivered to the core strand repeatedly completely around the entire supply source for the core strand and said core strand as it is delivered therefrom thereby to wrap said plural ply strand around the core strand and produce a composite strand, treating the composite strand to set the curl in the plies of the plural ply strand, and then applying a pulling force to the plural ply strand in the direction of the length of the composite strand thereby separating the plural ply strand into individual curled yarn ends which lie substantially parallel and in a non-twisted relation to the plural ply strand in the direction of the length of the composite strand.

5. The method of making curled yarn which comprises withdrawing a core strand from a source of supply, withdrawing from a stationary source of supply a plural ply strand of the yarn to be curled in which the individual yarn ends are straight and parallel and in a non-twisted relation, and delivering said plural ply strand with its individual yarn ends in such non-twisted relation to the core strand after the latter has been withdrawn from its source of supply, carrying the portion of the plural ply strand between its stationary source of supply and the point where it is delivered to the core strand repeatedly around the supply source for the core strand

thereby to wrap said plural ply strand around the core strand and produce a composite strand, treating the composite strand to set the curl in the plies of the plural ply strand, eliminating the core strand, and then applying a pulling force to the plural ply strand in the direction of the length of the composite strand thereby separating the plural ply strand into individual curled yarn ends which lie substantially parallel and in non-twisted relation.

6. A device of the class described comprising a rotary carrier, a bobbin carrying a core strand mounted on said carrier, means to rotate the carrier, means to withdraw the core strand from the bobbin as the carrier rotates and feed it forward in the axial line of the carrier, a stationary source of supply for the yarn to be curled from which is delivered a plural ply strand of such yarn made up of separate yarn ends having a parallel and non-twisted relation, said plural ply strand extending from its source of supply around the bobbin to the core strand, the point where said plural ply strand is delivered from its source being offset from the axial line of the bobbin, and means acting on the portion of the plural ply strand between its offset point of delivery and the point where it is delivered to the core strand to carry such portion repeatedly completely around the rotating bobbin thereby to wrap the plural ply strand about the core strand, the offset relation of said point of delivery of the plural ply strand causing said portion of the plural ply strand to be subjected to an increased pulling strain during a portion of each rotation of the carrier and to be substantially relieved from pulling strain during another portion of each rotation of the carrier.

7. A device of the class described comprising a rotary carrier, a bobbin carrying a core strand mounted on said carrier, means to rotate the carrier, means to withdraw the core strand from the bobbin as the carrier rotates and feed it forward in the axial line of the carrier, means for supplying at a point in the rear of the carrier and radially offset from the axial line thereof a plural ply strand of the yarn to be curled made up of separate yarn ends having a parallel and non-twisted relation, said carrier having a guide opening also offset from said axial line through which said plural ply strand extends to the core yarn as the latter is delivered from the carrier, whereby rotation of the carrier carries the portion of said plural ply strand between its source of supply and the point where it is delivered to the core strand repeatedly and completely about the bobbin, said plural ply strand because of the offset relation of its point of supply being subjected during a portion of each rotation of the carrier to an increased pulling strain by which it is fed forward and being relieved from pulling strain during another portion of each rotation of the carrier.

8. The method of making curled yarn which comprises withdrawing a core strand from a source of supply, withdrawing from a stationary source of supply a plural ply strand of the yarn to be curled in which the individual yarn ends are straight and parallel and in a non-twisted relation, delivering said plural ply strand with its individual yarn ends in such non-twisted relation to the core strand after the latter has been withdrawn from its source of supply, carrying the portion of the plural ply strand between its stationary source of supply and the point where it is delivered to the core strand repeatedly and

completely around the supply source for the core strand and around the core strand as it is delivered therefrom thereby to wrap said plural ply strand around the core strand and produce a composite strand consisting of a core strand and a plural ply strand composed of a plurality of individual yarn ends having a parallel non-twisted relation wrapped thereabout, treating the composite strand to set the curl in the plies of the plural ply strand, and then applying a pulling force to the plural ply strand in the direction of the length of the composite strand thereby separating the plural ply strand into individual curled yarn ends which lie substantially parallel and in a non-twisted relation.

9. A device of the class described comprising a rotary carrier, a bobbin carrying a core strand mounted on said carrier, means to rotate the carrier, means to withdraw the core strand from the bobbin as the carrier rotates and feed it forward in the axial line of the carrier, a stationary source of supply for the yarn to be curled from which is delivered a plural ply strand of such yarn made up of separate yarn ends having a parallel and non-twisted relation, said plural ply strand extending from its source of supply around the bobbin to the core strand, the point where said plural ply strand is delivered from its source being offset from the axial line of the bobbin, and means acting on the portion of the plural ply strand between its offset point of delivery and the point where it is delivered to the core strand to carry such portion repeatedly and completely around the rotating bobbin thereby to wrap the plural ply strand about the core strand and to apply to such portion of the plural ply strand both an increased pulling force and a reduced pulling force during each rotation of such portion about the bobbin.

10. The steps in the method of making curled yarn which comprise withdrawing a twisted core strand from a bobbin constituting a source of supply for said strand, rotating said bobbin about an axis which coincides with the line in which the core strand is delivered from the bobbin and in a direction to remove the twist from the core strand, withdrawing from a source of supply a plural ply strand of yarn to be curled in which the individual yarn ends are parallel and in a non-twisted relation, delivering said plural ply strand to the core strand after the latter has been delivered from its source of supply and the twist has been removed therefrom, carrying the portion of the plural ply strand between its source of supply and the point where it is delivered to the core strand repeatedly completely around the supply bobbin for the core strand while still maintaining the individual yarn ends of the plural ply strand in their parallel non-twisted relation, thereby to wrap said plural ply strand around the core strand and produce a composite strand in which the core strand is in a non-twisted condition.

11. A device of the class described comprising a source of core strand supply, means to feed said core strand forward from said supply source, a stationary source of supply for the yarn to be curled from which is delivered a plural ply strand having its individual yarn ends in parallel non-twisted relation, means acting on said plural ply strand after it is delivered from its stationary source of supply to carry it bodily and repeatedly completely about both the source of the core strand supply and the core strand as it is delivered therefrom and alternately to apply

11

to the plural ply strand as it is being carried about the core strand supply a pulling force sufficient to feed it forward and then to relieve said pulling force, thereby producing a composite strand comprising the core strand and the plural 5 ply strand wrapped thereabout with the individual yarn ends of said plural ply strand still in their parallel non-twisted relation.

12. A device of the class described comprising a rotary carrier, a bobbin carrying a core strand mounted on said carrier, means to rotate the carrier and the bobbin mounted thereon, means to withdraw the core strand from the bobbin as the carrier rotates and feed it forward in the axial line of the carrier, a stationary source of supply 10 for the yarn to be curled from which is delivered a plural ply strand of such yarn made up of separate yarn ends having a parallel and non-twisted relation, said plural ply strand extending from its source of supply to the core strand outside of the bobbin, and means acting on the portion of the plural ply strand between its source 15

10
